UNITED STATES PATENT OFFICE.

HENRY L. SCOTT, OF PROVIDENCE, RHODE ISLAND, ASSIGNOR, BY MESNE ASSIGNMENTS, TO HENRY L. SCOTT COMPANY, OF PROVIDENCE, RHODE ISLAND, A CORPORATION OF RHODE ISLAND.

TESTING CLAMP.

Application filed November 25, 1921. Serial No. 517,731.

This invention relates to improvements in the construction of specimen-gripping clamps employed in machines for testing the strength or stretch of materials, and has for its object to provide in combination with such a clamp an auxiliary clamp weight member for exerting a preliminary tension on a specimen prior to the closing of the jaws of the main clamp upon it.

10 A further object of the invention is to provide a jaw gripping cam for exerting a closing pressure on the main jaws and an anti-friction member through which the jaw-closing force of the cam is applied, whereby the cam may be caused to exert its maximum pressure owing to the fact that the contacting or operating friction of the cam for closing the jaws, is reduced to the minimum.

The invention further consists in the provision of links in which the closing cam is mounted, said links being adapted to be swung down out of the way permitting the jaws to swing to a wide open position to facilitate positioning the specimen in the auxiliary jaw member.

A still further object of the invention is the provision of means for adjusting the links to determine the most effective operating position of the cam.

30 With these and other objects in view, the invention consists of certain novel features of construction, as will be more fully described, and particularly pointed out in the appended claims.

35 In the accompanying drawings.

Figure 1 is a side elevation of my improved combination clamp and showing in dotted lines one jaw arm as being released by the cam and swung down to wide open 40 position.

Figure 2 is a top view of the clamp.

Figure 3 is a sectional side elevation illustrating the cam as exerting its closing force upon the jaws through a ball bearing element, and showing a fragmentary portion of one of the jaw cams.

Figure 4 is a sectional side elevation showing the cam operating means for adjusting the link pivoted to regulate the operating 50 position of the cam mounted in its opposite end.

Figure 5 is a detail of the auxiliary ten-

sion jaw removed from the main clamp and showing its biting jaw in open position.

It is found in practice in the operation 55 of machines for testing the strength or stretch of materials of advantage to apply a uniform tension to each of the specimens to be tested before the closing jaws of the main clamp upon them.

Then again it has been found that where a cam is employed for causing the clamp jaws to exert the necessary gripping pressure upon a specimen by directly engaging the jaw, that the sliding or rubbing friction of 65 the cam is so great as to limit its effective action, and I have, therefore, eliminated this closing friction by mounting the cam to exert its pressure through an anti-friction bearing element whereby the maximum closing pressure may be exerted upon the jaws with the minimum expenditure of force on the cam-operating lever, and I have also found it of advantage to mount the cam in the free end of a swinging link whereby the cam may be readily removed to permit the 70 free positioning of the specimen in the weight clamp and to also provide means for adjusting the pivoting end of this link to regulate the operating position of the cam to compensate for wear of parts and varying 75 thicknesses of the specimens being tested, and the following is a detailed description of one means by which each of these results may be accomplished:—

With reference to the drawings, 10 designates the main jaw arm of my improved clamp, which is preferably provided at its lower end with a boss 11 to which the tension rod or member 12 is secured and its upper end with a gripping faced member 13.

To the lower portion of this main jaw arm I have pivoted at 14 a swinging jaw arm 15, the same being provided with a gripping faced member 16 to cooperate with the corresponding member 13 on the main jaw, to grip the specimen 17 to be tested between them. This swinging jaw is provided with a spring 18 to normally press it to open position which is shown in dotted 90 lines in Figure 1.

A pair of link members 19 are pivoted each on opposite sides of the main arm 10 on the pin 20 and this pin is preferably

provided with a cam portion 21 having a toothed outer surface as at 22 to be engaged by a worm 23 mounted on a shaft 24, the latter being provided with a screw driver slotted end 25 by which it may be rotated to adjust the position of the cam 21 and so regulate the operating length of the links.

Between the outer or free ends of these links I have mounted a cam 26 on the shaft 27 and have connected to this shaft an operating handle 28 whereby the cam may be rotated, and this handle is provided with a stop lug 29 adapted to rest against the face of the jaw 15 to limit the inward throw of the cam handle.

It has been found in practice that where the working face of the cam directly engages the face of the jaw that the sliding friction of moving one surface upon the other is so great as to limit the operating power of the cam, and to obviate this serious difficulty in the action of the cam, I have inclosed the cam within a ball or anti-friction bearing, which in this instance comprises an outer raceway ring 30, an inner raceway ring 31 and a row of balls or rollers between the two. The inner ring being preferably shrunk on or otherwise connected to the cam face 26 while the outer ring is adapted to float and to engage the recessed portion 32 of the jaw 15 upon applying the closing pressure to the jaws whereby the clamping movement of the cam will cause the inner ring to rotate on the balls or anti-friction member while the outer ring will be retained by friction against rotation, by which construction the maximum closing power of the cam may be exerted on the jaws when pressure is applied to the operating handle.

By mounting this cam member in the free ends of the pivot links 19, upon swinging the cam handle outwardly the links are released to be dropped into the dotted position illustrated in Figure 1, to permit the arm 15 to swing to its wide open position to facilitate positioning the specimen between the jaws of the auxiliary preliminary tension weight 33, which weight is provided with a weighted body portion 34 mounted to slide on a pair of vertical rods 35 in the main jaw arm 10 and this body portion is provided with a clamp jaw 36 pivoted at 37 and normally pressed to closed position by a spring 38.

In operating the clamp it is only necessary to throw the cam operating handle outwardly to permit the links to be dropped down into dotted position illustrated in Figure 1, when the pivot jaw 15 may be swung to wide open position. The lower end of the specimen 17 is then gripped by the jaw 36 of the weighted clamp 33 whereupon this clamp exerts a given tension upon each of the specimens alike before the jaws of the

main clamp are closed upon them. It is now only necessary to raise the jaw 15 and the links with its cam up against the jaw and then by swinging the cam handle 28 inward the clamp jaw is caused to firmly grip the specimen to be tested.

In order to compensate for wear of the gripping parts to adjust for specimens of different thicknesses, it is only necessary to apply a screwdriver to the pin 24 to rotate its cam 21 and so regulate the operating length of the links 19 the operating position of the binding cam.

The device is very simple and practical in construction and by its use a uniform tension may be applied to each of the different specimens tested before being clamped and also by the use of the anti-friction bearing on the operating cam the maximum gripping action of the jaws on the specimen may be produced.

The foregoing description is directed solely towards the construction illustrated, but I desire it to be understood that I reserve the privilege of resorting to all the mechanical changes to which the device is susceptible, the invention being defined and limited only by the term of the appended claims.

I claim:

1. A clamp having a pair of relatively movable jaw members mounted to be separated for the reception of the work, a cam for exerting a closing force on said jaws, a ball bearing unit through which pressure is applied by said cam to said members, said unit comprising an inner shell fixed to said cam, an outer shell rotatable relatively thereto, said shells being grooved to provide a raceway between them, and anti-friction balls in said raceway through which pressure from one shell to the other is applied.

2. A clamp having a pair of relatively movable jaw members mounted to be separated for the reception of the work, a cam for exerting a closing force on said jaws, a ball bearing unit through which pressure is applied by said cam to said members, said unit having relatively rotatable inner and outer portions, said inner portion fixed to said cam and said outer portion engaging one of said jaw members, a handle for rotating said cam whereby a closing pressure may be exerted on said member without frictional sliding action between said outer portion and its engaged jaw member.

3. A clamp having a pair of relatively movable jaw members mounted to be separated for the reception of the work, a cam for exerting a closing force on said jaws, an anti-friction unit having relatively rotatable inner and outer portions encircling said cam through which pressure is applied by said cam to the jaw members, anti friction means between said inner and outer portions, said inner portion fixed to said cam

to move therewith relatively to said outer portion over said anti friction means in the exerting of a closing pressure on said members.

- 5 4. A clamp having one fixed and one movable jaw, a link pivoted at one end to said fixed jaw, a cam acting through said link for closing said jaws, a ball bearing element having relatively rotatable inner and outer portions with anti-friction balls therebetween encircling said cam and through which pressure is applied for closing said jaws, said inner and outer portions being fixed to said cam to move therewith relatively to said outer portion, and said link being movable about its pivot when said cam is in released position to permit the movable jaw to swing open for the reception of the work.
- 10 5. A clamp having one fixed and one mov-

able jaw, a link pivoted at one end to said fixed jaw, a cam carried by said link, an anti-friction member on said cam and acting through said link for closing said jaws, means whereby the link may be moved to withdraw the cam from operating position to permit the movable jaw to swing to a wide open position, and means for adjusting said link to regulate the operating position of said cam.

6. A clamp having one fixed and one movable jaw, a link, an adjustable eccentric through which said link is connected to said fixed jaw, cams mounted on the opposite ends of the link, and means for rotating said eccentric to adjust the relative operative position of said cam.

In testimony whereof I affix my signature.

HENRY L. SCOTT.
